UNITED STATES PATENT OFFICE.

GEORGE A. ELLSWORTH, OF ALGIERS, LA., ASSIGNOR OF TWO-THIRDS TO EDWARD QUINN, OF SAME PLACE, AND CHARLES MINNIGERODE, JR., OF NEW ORLEANS, LOUISIANA.

SEAL-LOCK.

SPECIFICATION forming part of Letters Patent No. 269,033, dated December 12, 1882.

Application filed June 7, 1882. (No model.)

To all whom it may concern:

Be it known that I, GEORGE ARTHURS ELLSWORTH, a resident of the town of Algiers, parish of Orleans, and State of Louisiana, have invented a certain new and useful Improvement in a Combination Seal-Lock and Label; and I do hereby declare the following to be a full, clear, and correct description of the same, reference being had to the annexed drawings, making a part of this specification.

This invention provides a means for locking, sealing, and labeling the doors of cars or other vehicles, the doors and windows of buildings or apartments, as well as the covers of boxes and other packages. The construction and arrangement of the parts are such that when once applied the device cannot be unlocked or the door or cover opened without evidence of the same being recorded on one of the parts of the invention.

My invention consists of two hooks, one having its point at about a right angle to the shank thereof, and the other with a rounded or curved end and sharpened points. The straight end of the latter is made round, in order that it can be turned in a similarly-shaped hole in the body of the car or where else applied. This end is notched on one of its sides, so that when it is inserted to its proper depth therein it shall be engaged by a catch, and thus be securely locked in position. The catch is forced back so as to permit of the withdrawal of the hook by turning the latter so as to bring a smooth surface opposite the same. The right-angle hook is permanently secured to the door, window, or cover, with its point in an opposite direction from the location of the detachable hook, and the said door, window, or cover has an arc-groove cut therein, beginning at its rear edge and extending to a point on a straight line drawn between the location of the two hooks, and with a radius from the shank of the movable one, as shown in the drawings, so that in the practice of the invention the point of the curved portion may operate therein. A label containing requisite information is designed to be engaged by the aforesaid hooks by first slipping one end of the same over the immovable hook,

leaving its free end to extend over the edge of the door, window, or cover, as the case may be, and the hole containing the catch above mentioned. The shank of the second hook is then pressed through the label and into the hole made for its reception until caught by the catch thereof, the point of the curved end in the meantime piercing the label and entering the groove which is made for its reception. The label cannot thereafter be removed without first releasing the movable hook, to do which it must be turned sufficiently to bring a smooth surface in contact with the catch, thereby unlocking the same. This movement causes the curved point to follow the arc-groove, thus necessarily cutting a similarly-shaped curve in the label, thereby clearly indicating that the same has been tampered with.

In the accompanying drawings my invention is shown in its application to freight-cars.

Figure 1 represents a side elevation of a car provided with my invention. Fig. 2 is a horizontal section of one of the sides thereof; and Fig. 3, a detached label, as after having been used.

The letter A indicates the body of a car, B one of its doors, and C the ordinary fastening of the same.

D represents the stationary hook.

E is the label, in which holes are made by slipping the same over the stationary hook, and by afterward forcing the points of the detachable hook F through the opposite end thereof.

The letter g designates the notch in the shank of the detachable hook, and h the catch whereby the said hook is secured in position, and i the arc groove in which the curved hook operates.

From the above description it will be seen that the door cannot be opened until the detachable hook has been withdrawn; that the said hook cannot be taken out until it has been turned about one-quarter around, which cannot be done without destroying or in a manner defacing the label, which acts as a seal and label combined, upon which can be printed or written all the particulars—if on a car, where from, where to, number of car, con-

tents, and any instructions as to disposition of car when empty; or any private stamp or signature of an agent or official can be put on label, either on the front or back thereof.

5 Having described my invention, what I claim as new, and desire to secure by Letters Patent, is—

The combination of the door B, having an external hook, D, and arc-groove *i*, the car body A, and label E, with the curved hook F,

having notch *g*, and the catch *h*, all arranged to operate as described, and for the purpose set forth.

In testimony whereof I hereunto sign my name.

GEORGE ARTHURS ELLSWORTH.

In presence of—

P. J. FINNEY,
J. C. HUBBELL.
